SPRING-CONTROLLED MECHANISM

George Carwardine, Bath, England, assignor of one-third to Herbert Terry & Sons Limited, Redditch, England, a company of Great Britain

Application October 14, 1937, Serial No. 169,014
In Great Britain October 31, 1936

15 Claims. (Cl. 188—167)

In servo-assisted mechanism, such as servo-assisted brake mechanism of a motor vehicle, in which two surfaces have to be moved into and out of engagement with each other and have to be forced tightly together when they are in engagement, it is often important that the servo device be brought into action in strict timed relationship with the relative movement of the surfaces. Thus, in the case of servo-assisted vehicle brakes it is usually desirable for the servo device to be rendered operative almost exactly at the moment when the braking surfaces make contact and for the servo device thereafter to exert a rising force effort increasing the pressure between the surfaces in step with the operation by the driver of the brake lever or pedal. Now it will be appreciated that in the event of the surfaces becoming worn, the point in the movement of the lever or pedal at which the braking surfaces make contact will change, so that unless the servo device is to get out of phase in its operation relatively to the time taken to bring the surfaces into contact, the servo device must be arranged to start delivering its contribution to the force necessary for increasing the pressure between the surfaces later than in the case where the surfaces are unworn. An aim of the invention is, therefore, to provide servo mechanism for operation in association with friction surfaces which has no effect on the operations of bringing the surfaces into and out of engagement, but which, as soon as the surfaces make contact, and only when they make contact, expends energy in pressing the surfaces tightly together.

According to the invention, mechanism, provided with a servo device for exerting pressure between two engaging surfaces and with a force-transmitting member that takes part in bringing the surfaces into and out of engagement, is furnished with a gripping mechanism which is so associated with the force-transmitting member and the servo device, that the clutch permits the servo device to remain inoperative as the force-transmitting member is moved to bring the surfaces into engagement but that the gripping mechanism is operated to render the servo device capable of exerting pressure between the surfaces as soon as the force-transmitting member experiences reaction due to the engagement of the surfaces. The gripping mechanism may comprise elements which are caused to engage each other when the force-transmitting member experiences the reaction due to the engaging surfaces, and provide a connection through which or against the reaction of which the servo device

acts to increase the pressure between the surfaces. When the mechanism is incorporated in the braking system of a vehicle, the brake pedal or lever is arranged to undergo an initial movement in applying the brakes during which the force-transmitting member is moved through the medium of the pedal lever to bring the braking surfaces into engagement. Then, when the force-transmitting member experiences the resistance due to contact between the surfaces, further movement of the pedal lever relatively to the force-transmitting member results in the operation of the gripping mechanism. In this case the said transmitting member is connected through the medium of the usual brake linkage to the brake shoes, and in the initial movement there is no resistance to the movement of the force-transmitting member except that due to friction and that due to the light springs in the brakes which tend always to withdraw the brake shoes from the drums.

In order that the invention may be clearly understood and readily carried into effect, various mechanisms, in accordance therewith, for controlling vehicle brakes will now be described by way of example with reference to the accompanying drawings, in which—

Figure 1 is a side elevation of one mechanism partly in section;

Figure 2 is a side elevation of a second mechanism;

Figure 3 is a sectional plan of part of a modification of the mechanism of Figure 2;

Figure 4 is a side elevation of a third mechanism;

Figure 5 is a section on the line V—V in Figure 4;

Figure 6 is a sectional elevation of a fourth mechanism;

Figure 7 shows a detail of the mechanism of Figure 6 to an enlarged scale;

Figure 8 shows the view seen when looking in the direction of the arrow VIII in Figure 7;

Figure 9 is a sectional elevation of a fifth mechanism;

Figure 10 is a sectional elevation of a sixth mechanism;

Figure 11 is a side elevation of a modification of the mechanism of Figure 10;

Figure 12 is a diagrammatic elevation of part of a further modification of the mechanism of Figure 2.

Figures 13, 14 and 15 are diagrammatic perspective views each showing the mechanism of Figure 1 connected to brakes through a linkage,

these figures respectively showing the parts in three stages in their operation.

In the mechanism of Figure 1, the arrangement is such that the vehicle brakes are applied through the medium of a linkage including a link 5 pivoted to a force-transmitting member in the form of a lever 2 which in turn is under the control of an operating element constituted by a pedal lever 1. When the latter is moved so as to apply the brakes it is swung about the axis of a spindle 6 through a small initial angle as the brake shoes are brought into contact with the brake drums. During this initial movement, the lever 2 moves as if integral with the lever 1, the lever 2 being held against a stop 3 on the lever 1 by a spring 4. As soon, however, as the brake surfaces engage, there is substantial resistance to further movement of the lever 2. The result is that the continued movement of the pedal lever 1 causes the spring 4 to extend while relative movement occurs between the levers 1 and 2 resulting in the engagement of a ratchet clutch which puts a servo device into connection with the brake operating linkage. This ratchet clutch comprises a lever 7 carrying teeth 8 and a member 9 carrying an arcuate row of teeth 10. The teeth 8 are drawn into engagement with the teeth 10 by a link 11 which, as the pedal lever 1 swings away from the lever 2, draws the lever 7 about its pivot 7a, at the upper end of the lever 2, towards the member 9. The clutch member 9 is pivoted on the spindle 6 and when engaged by the clutch lever 7 is swung as a unitary assembly with the pedal lever 1 and force-transmitting lever 2 about the common axis of the spindle 6.

The servo device comprises a telescopic strut 12, the two parts of which are formed respectively with plane surfaces bearing respectively against a fixed pivot pin 13 and against a pivot pin 14 mounted on the clutch member 9. A compression spring 15 tends always to expand the strut. Before the ratchet clutch is engaged, the servo mechanism is in the position shown in Figure 1 with the axis of the pin 14 beneath the plane containing the axes of the spindle 6 and pin 13 and the spring 15 tending to swing the telescopic strut anti-clockwise about the axis of the pin 13 (by reaction on the clutch member 9). Such anti-clockwise motion is prevented by engagement with a plate 16 forming part of the fixed supporting structure for the mechanism. It will be seen, therefore, that during a very short period at the beginning of the anti-clockwise motion of the clutch member 9, the spring 15 is compressed as the pin 14 is raised to the dead-centre position in alignment with the pin 13 and the spindle 6. Then, when the pedal lever 1 has been moved far enough to cause the clutch member 9 to carry the strut beyond the dead-centre position, the spring 15 is able to expand. Further movement of the brake pedal 1 is therefore accompanied by a corresponding amount of expansion of the servo spring 15 which, as it expands, plays the predominant part in increasing the pressure between the braking surfaces. The motion of the pedal lever 1 and the expansion of the spring 15 necessary to bring about this increase in pressure between the braking surfaces is rendered possible by the straining of the linkage connected between the lever 2 and the brake shoes.

After the pin 14 is passed over the dead-centre position to a position such as that indicated by A in Figure 1, the force due to the driver pro-

vides only a very small proportion of the total force serving to press the braking surfaces tightly together. As soon, however, as the driver relaxes his pressure on the pedal lever 1 the energy stored in the strained linkage is able to overcome the servo spring 15 and return the parts to their initial positions.

This action will be better understood with reference to Figures 13 to 15 which show diagrammatically one method of connecting the mechanism of Figure 1 to the two rear brakes of a vehicle. These figures show the link 5 connected to one of two levers 210 fixed to a shaft 208 mounted to turn about its axis. The other lever 210 is connected to the middle one of three levers 206 fixed to a shaft 205 mounted to turn about its axis. The two outer levers 206 are connected respectively by links 204 to levers 203 by which the pairs of brake shoes 200 are operated. The links 5, 207 and 204, together with the levers 210, 206 and 203, and the shafts 208 and 205, constitute the aforesaid brake operating linkage. When the parts are in the positions of Figure 13, the servo mechanism is in the state shown in Figure 1 and the brake shoes 200 are separated from their associated brake drums 201, the shoes being held in these positions by light springs 202, each acting between its respective pair of shoes. In the first part of the movement of the brake pedal 1 to apply the brakes, the pedal is moved from the position of Figure 13 to that of Figure 14, so that the shoes 200 are brought into contact with the inner surfaces of the brake drums 201. In this movement the only resistance is that due to the light springs 202 and that due to friction. This resistance is not sufficient to cause the spring 4 to stretch appreciably, so that the pedal lever 1 and the lever 2 move as a unit about the axis 6. When, however, the brake shoes 200 make contact with the brake drums 201, the resistance to movement of the lever 2 suddenly increases very considerably so that, upon a further movement of the pedal lever 1, the lever 2 is momentarily held from following while the spring 4 is stretched and the lever 7 is swung through the link 11 to cause the ratchet clutch to engage. Then, due to this engagement, the spring 4 can stretch no further and the levers 1 and 2 again swing as a single unit about the axis 6. The clutch member 9 now also partakes of this movement which, in view of the brake shoes 200 being prevented from further movement by their engagement with the brake drums 201, is permitted only by the resilience in the brake linkage. In the first small fraction of the movement of the member 9, the telescopic strut 12 is swung over its dead centre position. Then the relaxing servo spring 15 exerts, due to the increasing obliquity of the telescopic strut 12, a rising force effort assisting the operator in increasing the pressure between the contacting brake surfaces. The parts eventually reach positions such as shown in Figure 15.

The linkage shown in Figures 13 to 15 represents the kind of linkage usually employed in mechanical brake systems. Being metallic, it has considerable resilience. It obeys Hooke's law and may be regarded as a simple spring. Therefore, as the servo device is moved to the position of Figure 15, the spring constituted by the linkage is strained, one end of this linkage being held firm by the engagement of the drums 201 with the shoes 200. This straining is made up of torsion in the shafts 205 and 208, stretch in the links 204, 207 and 5 and bending in the 75

levers 203, 206 and 210. Such straining occurs normally in the operation of mechanical brake systems, in the absence of servo assistance. The latter is provided to relieve the driver of much of the effort that would otherwise be necessary to effect the straining of the linkage.

At any point in the movement of the servo spring 15 on the effective side of its dead centre position, it exerts a force which is somewhat less than the opposing force exerted by the strained linkage at that point. The difference is made up by the effort exerted by the driver on the pedal lever 1. Thus, when the driver's effort is removed, the strained linkage, being stronger than the servo device, returns the servo spring to the dead centre position. In the condition of Figure 15, for example, the strained linkage may be regarded as pushing hard against the brake shoes at one end to cause considerable friction between the brake surfaces and as pushing hard against the combined effort of the servo spring and the driver at the other end. When the driver removes his effort, the equilibrium is upset and the strained linkage relaxes while it returns the servo spring 15 to dead centre. It is true that the force due to the relaxing linkage decreases but the opposing force due to the servo spring also decreases and remains less than the force due to the strained linkage until the dead centre position is reached.

In some vehicles the brake linkage may not be such as to permit sufficient movement of the lever 2 and a corresponding transference of energy from the servo spring 15 and from the driver's foot to the brake linkage. Then, a further spring, such as the spring 209 indicated by dotted lines in Figure 15 can be inserted to form part of the brake linkage. The insertion of this spring is tantamount to putting one spring in series with another, the brake linkage being, as mentioned above, in the nature of a spring.

It may be noted that, as soon as the pin 14 (Figure 1) passes beyond the dead-centre position during the application of the brakes, the force due to the pressure of the driver's foot is transmitted to the link 5 through the link 11 and through the assembly consisting of the parts 2, 7 and 9. The rows of teeth 8 and 10 are so shaped that during the initial movement to bring the pin 14 to the dead-centre position, they remain in engagement and that after the dead-centre position has been passed the expanding spring 15 keeps them in engagement. When the strained linkage is allowed to return the strut 15 to the dead-centre position the two parts of the ratchet clutch are still held together, as in the brake-applying movement, on account of the opposition of the stresses respectively in the linkage and in the spring 15 tending to turn the members 2 and 9 in opposite directions, the teeth being so shaped that the spring 4 cannot separate them. When the dead-centre position is passed on the return movement the forces, by then very small, due respectively to the relaxing linkage and the spring 15 are in the same direction so that the spring 4 is able to separate the two parts of the clutch.

As wear in the braking surfaces takes place, the point in the brake-applying movement of the levers 1 and 2 at which the ratchet clutch is brought into action varies, the teeth 8 engaging the row of teeth 9 further and further along that row.

Referring now to the mechanism of Figure 2, when an operating element or pedal lever 17 in

that mechanism is caused to undergo its small initial movement prior to the engagement of the braking surfaces, a force-transmitting member or lever 18 is swung through the medium of links 19 which connect the lever 18 with a unit 20, 5 21, which is, in turn, pivoted to the lever 17. The lever 18 is connected to the brake shoes through the medium of a linkage including a compression link 22. When the mechanism replaces the servo mechanism shown in Figures 13 to 15, the link 22 is arranged to replace the link 5 and to push on the corresponding lever 210. The unit 20, 21 comprises a pair of links 20 and a pair of levers 21, the latter being held, in the initial movement, by a spring 23 against stops 24 on the links 20. The levers 21 carry friction shoes 25 which slide freely on a square tube 26. When the point at which the braking surfaces come into contact is reached, the continued movement of the pedal lever 17 results in relative movement between the links 20 and the levers 21, which hitherto have behaved as a unit, the springs 23 being extended while the lever 18 remains substantially stationary. The movement of the levers 21 about the axis at which they are connected to the links 20 results in the shoes 25 being moved closer together and gripping the square tube 26.

When the square tube 26 has been firmly gripped by the shoes 25, continued movement of the pedal lever 17 causes the links 20 to thrust the shoes 25 and the tube 26 as a unit to the right. The tube 26 engages slidingly within a guide 26a and fits over the actuated rod 27 of a spring servo unit S, including a servo spring S¹ which initially lies slightly to one side of a dead-centre position with respect to axes A and A¹ of members S² and S³ between which the spring S¹ is connected and which have arcuate surfaces S⁴ and S⁵ which roll on each other as the rod 27 is moved longitudinally. The members S² and S³ are pivoted respectively to a fixed rod S⁶ and to the rod 27 which is constrained to move in alignment with the rod S⁶. During a small initial part of the movement to the right of the tube 26, 45 the rod 27 is pulled to the right by springs 28 connected between pins 29 and 30 mounted respectively on the tube 26 and the rod 27. The springs 28 are strong enough not to expand appreciably during this movement, in which the spring S¹ is brought to its dead-centre position. As soon, however, as the servo spring S¹ in the unit S passes over its dead-centre position to its operative side thereof there is no longer tension between the tube 26 and the rod 27 but the servo 50 spring forces the pin 30 hard against the end of the tube 26, transmitting force through the latter, the shoes 25, the links 19 and the lever 18 to the brake linkage. The servo spring then plays the predominant part in straining the linkage so as to force the braking surfaces tightly together. When the driver's comparatively small contribution to the straining of the brake linkage has been removed, the force stored in the latter is sufficient to overcome the servo springs 65 and return the parts to their initial positions.

A small yielding catch 31 is provided to locate the tube 26 in the initial or "fully off" position of the servo unit.

The springs 28 are provided in case circumstances should arise that cause the servo rod 27 to be shot to the right, when the pedal lever 17 is in the initial position shown in Figure 2 and the shoes 25 are consequently not gripping the tube 26. If this should happen the brakes could 75

not be applied in the absence of the springs 28 because the shoes 25 would simply grip the rod 26 and prevent the pedal lever 17 from being moved further. The springs 28, however, allow 6 the tube 26 to be moved to the right relatively to the rod 27 if these abnormal conditions arise, the brakes being applied by foot pressure without any help from the servo unit S.

Figure 3 shows a modification of the construction in Figure 2 in which the shoes 25 are replaced by wedge members 32 bearing on each side of the square tube 26. The wedge members 32 are connected to the pedal lever 17 by a pair of links 33, the latter corresponding to the links 20. 15 During the initial movement to bring the controlling surfaces into contact, thrust is transmitted, from the links 33 and the wedge members 32, through a spring 34 to an external member 35 which in turn is connected by a pair of links 36, 20 equivalent to the links 19, to the lever 18. During this movement, the wedge members 32 and the external member 35 do not move relatively to each other, but as soon as the braking surfaces engage, the spring 34 yields so that the wedge members 32 move to the right relatively to the external member 35. This relative movement results in the inclined surfaces on the wedge members 32 closing upon inclined surfaces on the external member 35 so that rollers 37 are gripped 25 between the surfaces and the wedge members 32 are locked to the tube 26.

In the mechanism of Figures 4 and 5 the moving parts are supported between two plates 38 which, in turn, are connected through the medium 35 of bushes 39 to the vehicle chassis. A spindle 40 carrying a spacing sleeve 41 extends between the plates 38, and the sleeve 41 serves as a fulcrum for a rotatable force-transmitting member 42 connected by linkage, including a link 43, to 40 the brake shoes. The link 43 corresponds to the link 5 in Figures 13 to 15. The rotatable member 42 is formed, as shown in Figure 5, with a flange portion and a bush portion through which the sleeve 41 passes, while an annular plate 44 is screwed on to the end of the bush portion remote from the flange portion. A pedal lever 45 is secured to a flange member 46, pivotally mounted upon the outside of the bush portion of the rotatable member 42. The flange member 46 is connected by pins 47 to a flat ring 48, the arrangement being such that the flange member and ring must always rotate together about the axis of the sleeve 41 but are capable of independent relative movement along that axis.

55 During the initial movement of the brake pedal to bring the braking surfaces into contact, the flange member 46 rotates, carrying the rotatable member 42 with it, these two parts being drawn together by springs (not shown). However, 60 when the resistance due to the engagement of the braking surfaces holds up the member 42, these springs yield, while the relative movement between the flange member 46 and the member 42, resulting from further movement of the pedal 65 lever 45, causes balls 49, located in a ball race 50, to travel up the inclined surfaces of conical members 51 and 52, carried respectively by the rotatable member 42 and the flange member 46. The latter is thus forced axially to the right, as 70 viewed in Figure 5, relatively to the ring 48, and a clutch element 53, bearing friction material 54 on each face, is gripped firmly between the flange member 46 and the ring 48, the latter being prevented from moving axially to the right by thrust ball bearings, in a ball race 55, which, in turn, 75

bear against the annular plate 44. The clutch element 53 is, as shown in Figure 5, pivotally mounted on a sleeve integral with the flange member 46.

As soon as the clutch element 53 has been firmly gripped, the continued movement of the pedal lever 45 causes a pair of pins 56, carried between pairs of ears forming part of the clutch element 53, to pass over dead-centre positions relatively to a pair of pins 57 carried respectively by a pair 10 of double levers 58 pivoted at their upper ends about fixed axes 59 on the plates 38. A pair of struts 60 extend, as shown in Figure 4, between the pins 56 and 57, and as soon as the dead-centre position has been passed, a spring 61 is able to 15 exert a turning moment on the clutch element 53, so that during continued movement of the pedal lever 45 the relaxing spring 61 assists in a substantial manner the forcing together of the braking surfaces. The struts 60, through which the spring force is transmitted to the clutch element 53, are formed, as shown in Figure 4, with apertures, the surfaces of which have flat portions 20 against which the pins 56 and 57 bear. As in the previously described examples, when the pedal lever 45 is released, the strained brake linkage is able to overcome the spring 61 and, in relaxing, returns the clutch element 53 to and beyond the dead-centre position, the final movement of the parts to the positions shown in Figures 4 and 5 being assisted by the aforementioned springs between the rotatable member 42 and the flange member 46.

In the form of the invention shown in Figures 6 to 8, a pedal lever 62 is arranged to be swung 35 in the direction of the arrow B in order to apply the brakes. The pedal lever 62 is divided within the casing into two parallel arms 62a between which are pivoted a telescopic strut 63 and a connecting member 64. The latter comprises 40 two parallel parts 64a joined by transverse parts 64b carrying respectively a pair of pins 65 in recesses, the member 64 being in the form of the letter H when viewed in plan. The parts 64a of the connecting member 64 are formed with parallel slots 66 (see particularly Figure 7) which receive respectively pins 67 that are carried, in turn, respectively by two arms 68a forming part of a force-transmitting lever 68 that is connected through an appropriate linkage (like the linkage 203-210 shown in Figures 13 to 15) to the brake shoes. A compression spring 69 tends always to expand the telescopic strut 63 which is also pivoted between the arms 68a and, during the initial movement of the pedal lever 62, this spring keeps the pins 67 on the lever 68 against the left hand ends of the slots 66. Until the brake surfaces contact, therefore, the lever 68 swings with the pedal lever 62, the motion being transmitted through the spring 69. During this motion the connecting member 64 carries with it, as a unit, an assembly including a pair of toggle struts 70, two pairs of parallel levers 71, an abutment member 72, a servo spring 73, a pair of bell crank levers 74, a pair of bell crank levers 75, and 50 gripping elements referred to below. The outer ends of the toggle struts 70 bear respectively against pins 76, each of which extends between and is carried by one of the pair of levers 71. The servo spring 73 tends to swing the levers 71 about the axes of the pins 76 but is prevented from so doing by the bell crank levers 74 and 75 which are journalled on two trunnions 77 which project from each side of a U-shaped gripping element 78. Further, the servo spring 73, 55

prior to the engagement of the braking surfaces, produces horizontal components of force at the ends of the toggle struts 70 which cause the inner ends of the latter to tend to move to the right, but they are prevented from moving further to the right than is shown in Figure 6 by the abutment member 72.

As soon as the braking surfaces engage each other there is resistance to further clockwise movement of the lever 68. The result is that continued movement of the pedal lever 62 causes flanges 79 of the U-shaped gripping element 78 to bear hard against the pins 67 on the lever 68. Consequently, those parts which have hitherto moved as a unit with the connecting member 64, in the same relative positions, are caused to undergo relative movement. The bell crank levers 74 and 75 being pivoted to the gripping element 78, can no longer move to the left but 20 remain stationary, bearing hard against pins 80 on ears 81 integral with the gripping element 78, while the connecting member 64 carries the pins 65 up to and beyond their dead-centre positions relatively to the pins 76, the servo spring 73 being slightly strained as the dead-centre position is approached. As soon as the dead-centre position has been passed, the horizontal components of the reactions at the outer ends of the struts 70 are reversed so that the bell crank levers 74 and 75 are swung about the trunnions 77 away from the pins 80. When this happens, a gripping shoe 82 lying within the U-shaped gripping element 78 is forced downwards so that a fixed, square rod 83 is gripped tightly between the shoe 82 and the clutch element 78. This swinging movement of the bell crank levers 74 and 75 about the trunnions 77 is transmitted to the gripping shoe 82 by pairs of links 84 and 85. The links 84 connect pins 86, on the bell crank levers 75, with pins 87 on the gripping shoe 82, while the links 85 connect pins 88, on the bell crank levers 74, with pins 89 on the gripping shoe 82.

As the inner ends of the toggle struts 70 are moved to the left, so as to bring them beyond their dead-centre positions, the slots 66 in the connecting member 64 traverse the pins 67 on the lever 68 until the right hand ends of the slots 66 bear against pins 67. The effort exerted on the pedal lever 62 is then transmitted directly through the connecting member 64 to the lever 68, the spring 69 remaining in its compressed state while the pressure between the braking surfaces is increased. The effort necessary to bring about this increase in pressure is, of course, primarily due to the servo spring 73 exerting a longitudinal thrust to the left on the connecting member 64 through the medium of the toggle struts 70. The reaction of the servo spring 73, which would otherwise simply tend to move the pairs of levers 71 to the right without transmitting any thrust through the connecting member 64, is taken by the gripping elements which are held firmly in engagement by the servo spring 73 acting through the bell crank levers 74 and 75. As in the previous constructions, the strained linkage between the lever 68 and the brake shoes and, subsequently, the spring 69, return the parts to their initial positions shown in Figures 6 to 8, when the quantum of effort due to the driver is removed.

It will be seen that the construction shown in Figures 6 to 8 differs somewhat substantially in principle from the constructions shown in Figures 1 to 5. Thus, while the parts of the

gripping mechanism in each of the constructions of Figures 1 to 5 are caused by the driver's effort to engage before the servo spring is moved to the dead-centre position, the toggle struts 70 in Figure 6 are moved to their dead-centre positions prior to the engagement of the gripping parts by the effort due to the servo spring. Further, in each of the constructions of Figures 1 to 5, the servo spring transmits its effort through the gripping mechanism while in the construction of Figures 6 to 8, the gripping mechanism simply takes the reaction of the servo spring. In addition, while in each of the constructions of Figures 1 to 5, the driver's effort is transmitted through the gripping mechanism after the parts of the gripping mechanism have been caused to engage, in the construction of Figures 6 to 8 the effort exerted on the pedal lever 62 is transmitted directly to the lever 68 through the connecting member 64 when the toggle struts have passed beyond their dead-centre positions.

The underlying principles of the mechanism shown in Figure 9 are very similar to those of the mechanism of Figures 6 to 8. In Figure 9, a pedal lever 90 forms part of a toggle, the other link of which is a strut 91 which bears at one end on a pin 92, carried by the pedal lever 90, and at the other end on a pin 93, carried by a lever 94. A servo spring 95, before the braking surfaces are brought into contact, holds the toggle in the position shown in Figure 9 with the proximal ends of the two toggle members 90 and 91 tending to move to the left but being prevented from doing so by the engagement of a pin 96, on the pedal lever 90, with one end of a slot 97 in a lever 98. The lever 94 is pivoted at its right hand end to a bell crank lever 99 which, in turn, is pivoted at 100 to a plate 101. The latter is carried by links 102 and 103, pivoted at their upper ends to the casing containing the mechanism. The links 102 and 103 form with the plate 101 a parallelogram linkage. The servo spring 95 and the toggle members 90 and 91 are so arranged that during the initial movement of the brake lever 90, prior to the engagement of the braking surfaces, the servo spring and toggle simply act as if they were third and fourth links like the links 102 and 103. The initial movement of the brake lever 90, therefore, simply results in the plate 101 swinging to the right on its links 102 and 103, while the pedal lever 90, acting through a spring-loaded telescopic strut 104, swings a force-transmitting lever 105 in an anti-clockwise direction, the lever 105 being connected to the brake shoes through an appropriate linkage (like the linkage 203—210 shown in Figures 13 to 15).

As soon as the braking surfaces engage, the lever 105 can no longer swing in an anti-clockwise direction, so that the continued movement of the pedal lever 90 results in the compression of the spring 104, while the linkage, comprising the links 102 and 103 and the plate 101 are prevented from following the pedal lever 90 by the engagement of the right hand end of the lever 98 with a pin 106 on the lever 105. The toggle is consequently straightened and the pin 92 eventually passes over the dead-centre position relatively to the pin 93 and the axis 90a of the pedal lever 90.

Before the toggle reaches the dead-centre position, there is a component of force due to the servo spring 95 acting on the pivotal connection between the plate 94 and bell crank lever 99 in a direction such as to hold the latter against a stop 107 on the plate 101. As soon, however, as the toggle passes over the dead-centre position,

- the direction of this component of force is reversed, so that the bell crank lever 99 is swung about the axis 100, and acting through a strut 108, causes a friction gripping element 109 to press a rod 110 tightly against a second friction gripping element 111. The rod 110, which is pivoted at its right hand end to the casing, is thus tightly gripped between the gripping elements 109 and 111.
- 10 As soon as the pedal lever 90 passes over the dead centre position, a pin 112 thereon bears against a flat surface 113 on a strut member 114 held in a strap 115 which embraces both the pin 112 and a pin 116, which is carried by the lever 105 and which serves as a pivotal bearing for the right hand end of the strut member 114. The effort supplied by the driver is, therefore, transmitted through the pin 112 and strut member 114 to the lever 105. As the engaging braking surfaces are forced tightly together, the relaxing servo spring 95 surrenders its energy through the pin 112 and strut member 114, the effort being transmitted through the strut 91. It will be appreciated that this effort which, of course, is applied when the pin 92 is to the right of its dead-centre position, would be wasted in swinging the plate 101 to the left, were it not for the gripping elements which take the horizontal component of the reaction due to the servo spring 95 at the pin 93.
- 15 When the driver's effort is removed, the strained brake linkage is, as in the previous examples, able to overcome the spring 95, so that the parts are returned to the positions shown in Figure 9, first by the relaxing linkage and then by the relaxing spring 104. The purpose of this spring 104 requires, perhaps, a little more explanation, especially as it will probably have been noticed that the lever 98, bearing on the pin 106, would be sufficient to effect the initial movement, prior to the engagement of the braking surfaces, of the force-transmitting lever 105. When the latter is held up as a result of the engagement of the braking surfaces, the reason why force can be exerted on the pedal lever 90, during continued movement of the latter prior to the passing of the dead-centre position, is due to the resistance of the spring 104 and of the servo spring 95, the force being transmitted through these springs to hold the braking surfaces in contact. Now, as the servo spring 95 approaches its dead-centre position, i. e., its position of maximum stretch, its effect decreases, but the effect of the spring 104 increases as it is compressed. In other words, the spring 104 provides a rising-force resistance while the spring 95 provides a falling-force effort as it approaches its dead-centre position. Thus, if the servo spring was used alone, the force-transmitting lever 105 would have a chance to move slightly backward (i. e., clockwise) as the servo spring reached its dead-centre position. This state of affairs, combined with the effect of the expansion of the brake drums due to the heat of the actual braking might well mean that when the driver removed his pressure the stressed brake linkage would not be able to return the servo spring to and beyond the dead-centre position. The spring 104 is, therefore, provided to remove this risk.
- 20 The rising-force resistance provided by the spring 104, combined with the falling-force characteristic of the servo spring 95, maintains a more or less constant or slightly rising-force to resist the relative displacement between the pedal lever 90 and the force-transmitting lever 105. The spring
- 25 69 in the construction of Figures 6 to 8 functions similarly to the spring 104 in Figure 9.
- 30 In the mechanism of Figure 10 the brake pedal, not shown, is fixed to a spindle 117 to which is fixed a pedal lever 118. A pair of long levers 119 are mounted to swing freely about the spindle 117, the pedal lever 118 being located between these two long levers. When the brakes are in the "fully-off" position the parts of the servo mechanism are in the positions shown in Figure 10, and when the initial movement of the pedal lever 118 occurs for bringing the braking surfaces into contact, the pedal lever 118 is swung in an anti-clockwise direction. The pedal lever 118 is connected by a telescopic strut 120 to a lever 121 pivotally mounted on the long levers 119 by means of a journal 120. A servo spring 122 tends always to expand the telescopic strut 120, and in the initial positions of the parts, tends to cause the lever 121 to swing in a clockwise direction relatively to the long levers 119. The lever 121 is, however, prevented from swinging in this direction because a pin 123 thereon is in engagement with one of the long levers 119. The reaction exerted at the right hand end of the spring 122 also acts to hold the pin 123 in engagement with the lever 119 because the spring reacts against the pedal lever 118 and thence, through an extension 133 acts on the head 134 of a slidable rod 131, threaded at its left hand end 35 in a journal 135 so that this pull also tends to turn the lever 121, clockwise. Therefore, the pressure of the spring 122 at this phase of the operation keeps the clutch lever 121 as a rigid part of the long lever 119. The arrangement, 40 therefore, is such that during the initial anti-clockwise movement of the pedal lever 118, the long levers 119, the telescopic lever 120, and the lever 121 move as a unit with the pedal lever 118. The motion is transmitted to the brake 45 shoes through a force-transmitting lever 124 which is moved by the long levers 119 bearing upon rollers 125 carried by a strut 126 formed with a flat surface 127 that bears on a pin 128 carried by the lever 124. The flat surface 127 forms part of the boundary of an aperture in which the pin 128 lies. A similar aperture 130 is formed at the other end of the strut 126 and this contains a pin 129 carried by the pedal lever 118.
- 50 When the braking surfaces make contact, so that the lever 124 experiences substantial resistance to further movement, the pair of long levers 119 are held back by the rollers 125, downward movement of the latter being prevented by the pin 128 bearing against the flat surface 127. Thus, continued movement of the brake lever 118 takes place relatively to the long levers 119 and a spring 150 (equivalent to the spring 104 in Figure 9) is compressed while the right hand end of the telescopic strut 120 is moved to and beyond its dead-centre position. It may be mentioned that the two telescoping parts of the strut 120 are formed respectively with plane surfaces 136 and 137 which respectively bear against a pin 138, on the pedal lever 118, and a pin 139, on the lever 121. The dead-centre position, of course, is the one in which the axis of the pin 138 is in the same plane as the axes of the pin 139 and of the spindle 117.
- 55 The pivotal connection between the lever 121 and the long arms 119 is provided by the journal 140 which passes through slots 141 in the long arms 119 and which carries a roller 142. The latter, under the horizontal component of the

80 81

85 86

90 91

95 96

100 101

force due to the servo spring 122, is caused always to bear against a fixed arcuate rail 143 having its axis coincident with the axis of the spindle 117. As soon as the pedal lever 118 is caused to carry the pin 138 over the dead-centre position, the line of action of the force exerted by the servo spring 120 passes above the axis of the journal 140 and beneath the axis of the spindle 117. The turning moment due to the servo spring 122 upon the lever 121, is then anti-clockwise, so that the servo spring 122 tends to move the pin 123 away from the lever 119. This anti-clockwise movement of the lever 121 actually takes place quickly, because a spring 144, which is connected between the levers 119 and the lever 121 and which is held in tension so long as the servo spring 122 holds the pin 123 in the position shown in Figure 10, is released as soon as the strut 126 passes over the dead-centre position. The spring 144 is very much weaker than the spring 122 although the line of action of the latter is considerably closer to the axis of the journal 140, so that, in effect, the spring 144 only becomes effective when the moment due to the servo spring 122 is reversed. A gripping shoe 145, pivoted upon the clutch lever 121 is then brought sharply into engagement with the rail 143 under the combined influence of the two springs. This anti-clockwise movement of the lever 121, in effect, causes the roller 142 and the gripping shoe 145 to wrap upon the rail 143 so that the latter is firmly gripped. If the rail 143 is mounted on rubber bushes, the slots 141 can be dispensed with and the journal 140 carried in plain journal bearings in the long arms 119. In this case the roller 142 and the gripping shoe 145 will wrap upon and grip the rail 143 equally well.

When the dead-centre position has been passed, the pin 129 on the pedal lever 118 bears against the lower flat face of the aperture 130, so that upon further movement of the pedal lever 118, the effort exerted by the relaxing servo spring 122 has a downwardly-directed vertical component which assists the driver in turning the lever 124 further in an anti-clockwise direction, the force due to the driver and to the servo spring being transmitted through the strut 126. The reaction at the left hand end of the servo spring 122, which would otherwise simply cause this spring to swing the levers 119 in a clockwise direction instead of exerting a thrust through the strut 126, is taken by the gripping elements.

It will be noted that the pins 138 and 139 and their associated plane surfaces 136 and 137 at the ends of the telescopic strut 120 provide a form of pivotal joint which is used extensively in the other illustrated constructions. In each case the pins consist of hardened steel cylinders having their axes normal to the plane of movement. By this means the struts are articulated so as to move with negligible friction, the hardened plane surfaces merely rolling around their respective cylinders. In order that such rolling may be confined to a limited area on the plane surfaces, ears are provided at the outer ends of the struts, and these have apertures which engage the cylinders with sufficient looseness to allow the required degree of rolling to take place. In the case of the telescopic strut in Figure 10, these ears bear the reference numerals 147 and 148.

The reason why the rollers 125 are mounted on one side of the strut 126 is to ensure that this strut shall take up the position shown in Figure

10 relatively to the other parts in the initial state of the mechanism. The object of this is two-fold. Firstly, it allows the clearances of the bearing surfaces between the strut 126 and the pins 128 and 129 to be in the necessary relative positions. When the pin 129 contacts with the flat or plane part of the boundary of the aperture 130 the pins 128 and 129 roll on their respective plane surfaces under the force from the lever 118 as the latter is moved to force the braking surfaces together. This rolling action causes the strut 126 slightly to rotate in a clockwise direction. If the aforementioned clearance were not on the right side to allow this clockwise rotation the pins 128 and 129 would be compelled to skid on their respective plane surfaces. Secondly, the placing of the rollers 125 causes the pin 129 to enter a small recess 146 at one side of the aperture 130 when the parts are in the positions shown in Figure 10. The pin 129 and recess 146 together provide a form of catch preventing too ready movement of the pedal lever 118 from its initial position.

Figure 11 shows a modified form of gripping arrangement for the mechanism of Figure 10. In Figure 11 the rail 143 is replaced by two arcuate strips 149 interleaved at their ends between resilient rubber blocks 150b. A pad of friction material 151 is mounted to slide between the strips 149, and the long levers 119 carry pins 152 projecting between the strips 149 at each end of the pad 151, so that the latter swings with the long levers 119. When the lever 121 is swung in an anti-clockwise direction, the arcuate strips 149 are gripped tightly between the roller 142 and the shoe 145, while the pad 151 is gripped tightly between the strips 149.

In the various constructions described above the inertia of the force-transmitting member and the linkage connecting the latter to the brake shoes might, in the event of the driver giving the brake pedal a sudden jab, result in relative movement between the pedal lever and the force-transmitting lever before the braking surfaces contact, so that the clutch would be engaged prematurely. In order to eliminate this risk a weight may be provided, in such a manner as to ensure that the clutch shall not be operated and the servo spring caused to move over the dead-centre position until the braking surfaces contact, thereby eliminating any danger of the brake linkage being strained during the wrong part of the movement of the pedal lever, and the consequent risk of the parts not being returned to their initial positions when the driver's effort is removed from the brake pedal. For example, in the construction shown in Figure 2, the weight may be attached to extensions of the levers 21, these extensions being in a downward direction beyond the spring 23. In this case the inertia of the weight would be such that, during the initial movement of the pedal lever in the application of the brakes, it would tend to keep the clutch shoes 25 separated in spite of the tendency of the inertia of the brake linkage to cause these shoes to grip the square tube 26. Again, in the example shown in Figure 10, a counter-weight may be mounted on an arm extending from the telescopic strut to the right and in alignment therewith.

Figure 12 shows a modification of the construction shown in Figure 2. In Figure 12, a square tube 152a, equivalent to the tube 26 in

Figure 2, is attached at its right hand end to a servo unit S the same as the servo unit S in Figure 2. In order to apply the brakes, a pedal lever 150A, pivoted about a fixed axis 167, is swung in the direction of the arrow, and prior to the engagement of the braking surfaces, a force-transmitting lever 151a, pivoted about a fixed axis 168, undergoes equivalent movement, the pedal lever 150A being connected to the lever 151a through the medium of a link 153, a bell crank lever 155, a shoe 157, a three-armed lever 156 and a link 154. The bell crank lever 155 and the three-armed lever 156 are pivoted to the shoe 157 respectively at 163 and 164. During the initial movement, the bell crank lever 155, the three-armed lever 156, and the shoe 157 move as a unit to the left, without relative movement taking place between these parts, due to a spring 162 connected between the bell crank lever 155 and three-armed lever 156 holding stop projections 158 and 159 on these levers in contact with a stop surface 160 on the shoe 157. The link 153 and bell crank lever 155 are pivoted together at the axis of a roller 165 which is free to rotate independently of the link and the lever. Similarly, the link 154 and the three-armed lever 156 are pivoted together at the axis of a roller 166 which is free to rotate independently of the link and the lever. Thus, during the initial movement, prior to the contacting of the braking surfaces, the rollers 165 and 166 simply roll on the top of the square tube 152a, while the shoe 157 is carried to the left and remains out of engagement with the square tube 152a. When the braking surfaces contact, the force-transmitting lever 151 is held back as the pedal lever 150A continues to swing in a clockwise direction. The result of this is that the rollers 165 and 166 separate slightly, while the bell crank lever 155 swings in an anti-clockwise direction, and the three-armed lever 156 swings in a clockwise direction, the stop projections 158 and 159 moving upwards, away from the stop surface 160. The shoe 157 is therefore raised so that a layer of friction material on its upper surface engages the underside of the square tube 152a. The latter is thus gripped tightly between the shoe 157 and the rollers 165 and 166. Then, however, continued clockwise movement of the pedal lever 150A causes the rollers 165 and 166, the square tube 152a, and the shoe 157 to move to the left as a unit, causing the force-transmitting lever 151a again to swing in a clockwise direction under the combined force exerted by the servo unit and by the effort of the driver.

As the shoe 157 is lifted into tight engagement with the square tube 152a, the spring 162 is stretched. It will be seen that this spring is connected to the three-armed lever 156 at a point beneath the axis of the roller 166, while it is connected to the bell crank lever 155 at the axis of the roller 165. The reason for this is to ensure that when the rollers 165 and 166 are caused to separate, the three-armed lever 156 swings in a clockwise direction before the bell crank lever 155 swings in an anti-clockwise direction. This is necessary because under the action of the forces to which they are subjected, the roller 166 and the right hand end of the shoe 157 tend to wrap on to the square tube 152a, while the roller 165 and left hand end of the shoe do not. If the bell crank lever 155 operated before the three-armed lever 156, there would be a risk of the square tube

152a being shot forward under the action of the servo spring and releasing itself from the grip of the roller 165 and left hand end of the shoe 157 during its movement. Obviously, in the arrangement illustrated, the three-armed lever 156 acts prior to the bell crank lever 155 because the moment exerted by the spring 162 about the axis 164 is less than that exerted by the spring about the axis 163.

It will be seen that a weight 161 is mounted on 16 the three-armed lever 156, and the purpose of this weight is the same as that of the weights mentioned above that can be applied to the other illustrated constructions. In the event of the pedal lever 150a being given a sharp initial movement such that the force-transmitting lever 151a and the braking linkage (connecting the force-transmitting lever with the brake shoes) could not follow, due to their inertia, in the absence of the weight 161, the inertia of the weight 161 in 20 its sharp movement to the right would hold the stop projection 159 in engagement with the stop surface 160, preventing the operation of the gripping elements and forcing the force-transmitting lever 151a to follow the pedal lever 150a until the 25 braking surfaces contact. A similar weight can, if necessary, be applied to an extension of the bell crank lever 155, this extension extending from the upper end of the bell crank lever 155 upwards beyond the roller 165.

I claim:

1. Mechanism for bringing two friction surfaces into engagement, increasing the pressure between the surfaces when in engagement, and subsequently separating the surfaces, said mechanism comprising in combination, an operating element, a force-transmitting member adapted to be operatively connected to one of the friction surfaces and operatively connected to said operating element so as to be moved by a force applied to said operating element to bring the friction surfaces into engagement, a gripping mechanism connected to be operated by movement of said operating element relatively to said force-transmitting member when resistance to the movement of the latter is set up by engagement of the friction surfaces, and a servo spring arranged to be rendered effective, upon further movement of said operating element, to act through said gripping mechanism and to expend energy on said force-transmitting member in association with the force applied to said operating element to force the surfaces tightly together.

2. Mechanism for bringing two friction surfaces into engagement, forcing the surfaces tightly together when in engagement to increase the friction therebetween, and subsequently separating the surfaces, said mechanism comprising in combination a force-transmitting member adapted to be operatively connected to one of the friction surfaces, an operating element operatively connected to said force-transmitting member to move said force-transmitting member to bring the friction surfaces together during a first movement of said element and to undergo further movement 65 relatively to said force-transmitting member while the latter is held substantially stationary due to the reaction of the friction surfaces in engagement, a servo spring, and gripping mechanism, operatively associated with said servo spring, 70 said force-transmitting member and said operating element, to render said servo spring operative, upon the occurrence of the further movement of said operating element, to assist the forcing together of the engaging friction surfaces during 75

still further movement of said operating element.

3. Mechanism for bringing two friction surfaces into engagement, increasing the pressure between the surfaces when in engagement, and subsequently separating the surfaces, said mechanism comprising in combination an operating element, a force-transmitting member adapted to be operatively connected to one of the friction surfaces and operatively connected to said operating element so as to be moved by a force applied to said operating element to bring the friction surfaces into engagement, a resilient connection between said operating element and said force-transmitting member, a gripping mechanism having elements connected to be brought into engagement with each other by movement of said operating element relatively to said force-transmitting member when resistance to movement of said force-transmitting member is set up by engagement of the friction surfaces, and a servo spring operatively associated with said gripping mechanism to be rendered effective by said operating element upon the engagement of said gripping mechanism and arranged to expend energy on said force-transmitting member under control of said operating element upon further movement of the latter to force the friction surfaces tightly together.

4. In mechanism for controlling the engagement of braking surfaces, the combination of a force-transmitting member adapted to be operatively connected to one of the braking surfaces, an operating element connected to act upon said force-transmitting member to bring the braking surfaces into engagement, a gripping mechanism connected to be operated upon said force-transmitting member being held up by the resistance set up due to the engagement of the braking surfaces while movement of said operating element continues, and a servo device, including a spring to provide the servo force, normally free of said force-transmitting member and in stable equilibrium but connected to be rendered capable of acting on said force-transmitting member by means of said gripping mechanism, so that said servo device can come into action only when the braking surfaces have contacted.

5. Mechanism for bringing two friction surfaces into engagement, increasing the pressure between the surfaces when in engagement, and subsequently separating the surfaces, said mechanism comprising in combination an operating element, a force-transmitting member adapted to be operatively connected to one of the friction surfaces and operatively connected to said operating element so as to be moved by a force applied to said operating element to bring the friction surfaces into engagement, a gripping mechanism connected to be operated by movement of said operating element relatively to said force-transmitting member when resistance to the movement of the latter is set up by engagement of the friction surfaces, and a servo mechanism including a lever device mounted for movement from one side of a dead-centre position to the other side thereof and also including a servo spring in operative engagement with said lever device and arranged to hold said lever device slightly to one side of the dead-centre position while the friction surfaces are brought into engagement, said servo mechanism being rendered, by operation of said gripping mechanism, effective to expend energy, during the relaxing of said servo spring on the other side of the dead-centre position, on said force-transmitting member, and

said lever device being caused to pass to said other side of the dead-centre position by further movement of said operating element.

6. In mechanism for controlling the engagement of braking surfaces, the combination of a force-transmitting member adapted to be operatively connected to one of the braking surfaces, an operating element connected to act upon said force-transmitting member to bring the braking surfaces into engagement, a gripping mechanism having elements connected to be brought into engagement by the resistance set up upon the engagement of the braking surfaces holding up said force-transmitting member while movement of said operating element continues, and a servo device, including a spring to provide the servo force, normally free of said force-transmitting member and in stable equilibrium, but connected to said force-transmitting member by the engagement of said gripping elements, said servo device thus becoming effective by acting, through said gripping elements, upon said force-transmitting member only when the braking has actually begun.

7. In mechanism for controlling the engagement of braking surfaces, the combination of a force-transmitting member adapted to be operatively connected to one of the braking surfaces, an operating element connected to act upon said force-transmitting member to bring the braking surfaces into engagement, a gripping mechanism having elements connected to be brought into engagement by the resistance set up upon the engagement of the braking surfaces holding up said force-transmitting member while movement of said operating element continues, and a servo device, including a spring to provide the servo force, connected to be rendered capable of acting on said force-transmitting member only when said gripping elements are brought into engagement and provide an abutment against which said servo device acts.

8. Mechanism for bringing two friction surfaces into engagement, increasing the pressure between the surfaces when in engagement, and subsequently separating the surfaces, said mechanism comprising in combination an operating element, a force-transmitting member adapted to be operatively connected to one of the friction surfaces and operatively connected to said operating element so as to be moved by a force applied to said operating element to bring the friction surfaces into engagement, a gripping mechanism connected to be operated by movement of said operating element relatively to said force-transmitting member when resistance to the movement of the latter is set up by engagement of the friction surfaces, and a servo mechanism including a lever device mounted for movement from one side to the other of a dead-centre position and also including a spring in operative engagement with said lever device and arranged to hold said lever device slightly to one side of the dead-centre position while the surfaces are brought into engagement, said servo mechanism being so operatively associated with said gripping mechanism and the latter being so operatively associated with said force-transmitting member that, subsequently to the engagement of said gripping mechanism said lever device can be caused to pass over the dead-centre position whereupon said spring can, in relaxing, augment the force applied to said operating element to increase the pressure between the friction surfaces.

9. In mechanism for bringing two friction surfaces into engagement, increasing the pressure between the surfaces when in engagement, and subsequently separating the surfaces, the combination of an operating element, a force-transmitting member adapted to be operatively connected to one of the friction surfaces, a resilient connection between said operating element and said force-transmitting member whereby said operating member may be caused to move said force-transmitting member to bring the friction surfaces into engagement and may then be moved further while said force-transmitting member is held substantially stationary by the resistance set up by the engaging friction surfaces, a lever device mounted for movement from one side to the other of a dead-centre position, a servo spring operatively connected to said lever device and arranged to hold said lever slightly to one side of the dead-centre position while the friction surfaces are brought into engagement, and a gripping mechanism operatively associated with said operating element, said force-transmitting member and said lever device, said gripping mechanism being engaged to provide a connection between said lever device and said force-transmitting member by said further movement of said operating element and arranged, upon still further movement of said operating element, to carry said lever device over the dead-centre position, thereby rendering said servo spring capable of expending energy on said force-transmitting member.

10. In mechanism for bringing two friction surfaces into engagement, increasing the pressure between the surfaces when in engagement, and subsequently separating the surfaces, the combination of an operating element, a force-transmitting member adapted to be operatively connected to one of the friction surfaces, a resilient connection between said operating element and said force-transmitting member whereby said operating member may be caused to move said force-transmitting member to bring the friction surfaces into engagement and may then be moved further while said force-transmitting member is held substantially stationary by the resistance set up by the engaging friction surfaces, a lever device mounted for movement from one side to the other of a dead-centre position, a servo spring operatively connected to said lever device and arranged to hold said lever device slightly to one side of the dead-centre position while the friction surfaces are brought into engagement, said lever device being so associated with said operating element and with said force-transmitting member as to be forced over the dead-centre position by said further movement of said operating element, and a gripping mechanism connected to be operated by such forcing of said operating element over the dead-centre position and adapted to provide, when so operated, an abutment against which said servo spring can react in relaxing to expend energy in assisting the further movement of said force-transmitting member to increase the pressure between the engaging friction surfaces.

11. Mechanism for controlling the engagement of friction surfaces, said mechanism comprising in combination, a servo unit, a pivotally-mounted operating element, a pivotally-mounted force-transmitting member, a linkage including a resilient element connecting said operating element with said force-transmitting member and arranged to move as a rigid unit so long as said

force-transmitting member is free to be moved by said operating element but to undergo deformation when said operating element is moved while movement of said force-transmitting member is resisted, a gripping mechanism comprising a gripping element connected to said servo unit and gripping shoes mounted on said linkage and arranged to grip said gripping element when said deformation occurs so as to provide with said linkage and said clutch element an assembly whereby further motion of said operating element is transmitted to said force-transmitting member and to said servo unit, the latter being arranged thereupon to assist the further movement of said force-transmitting member during still further motion of said operating element.

12. The invention of claim 11 in combination with a further resilient element, connected between said gripping element and said servo unit, permitting movement of said gripping element in the event of said servo unit being disabled.

13. Mechanism for controlling the engagement of friction surfaces, said mechanism comprising in combination a force-transmitting member pivotally mounted about an axis, an operating element pivotally mounted about the same axis, means interposed between said element and said member operative to cause relative movement along said axis between said element and said member when relative movement about said axis occurs between the same, a further element, a gripping element pivotally mounted about said axis and interposed between said operating element and said further element to be gripped therebetween upon the occurrence of said relative movement along said axis, a lever pivotally connected to said gripping element and mounted for movement from one side to the other of a dead-centre position, and a servo spring operatively connected to said lever and adapted, when the latter is on one side of the dead-centre position, to transmit movement through said gripping element to said force-transmitting member, the latter being adapted for connection to one of the friction surfaces.

14. Mechanism for controlling the engagement of two friction surfaces, said mechanism comprising in combination, an operating element, a force-transmitting member adapted to be operatively connected to one of the friction surfaces, a spring connected between said operating member and said force-transmitting member to transmit movement of the former to the latter for bringing the friction surfaces into engagement, a strut mounted to provide a rigid connection between said operating element and said force-transmitting member after said spring has been strained due to the resistance set up by the engaging friction surfaces impeding movement of said force-transmitting member during continued movement of said operating element, a gripping mechanism, a lever device connected between said clutch device and said operating element, said lever device being mounted for movement from one side to the other of a dead-centre position, and a servo spring mounted to hold said lever device on one side of the dead-centre position, said lever device being so operatively associated with said force-transmitting member that when the latter is impeded, said lever device is forced over the dead-centre position by the continued movement of said operating member whereby said gripping mechanism is engaged to provide an abutment against which said servo

spring acts in relaxing to expend energy on said operating element during still further movement of the latter.

15. Mechanism for controlling the engagement of two friction surfaces, comprising in combination, an operating element, a force-transmitting member adapted to be operatively connected to one of the friction surfaces, a spring connected between said operating member and said force-transmitting member to transmit movement of the former to the latter for bringing the friction surfaces into engagement, a strut mounted to provide a rigid connection between said operating element and said force-transmitting member 10
15 after said spring has been strained due to the resistance set up by the engaging friction surfaces impeding movement of said force-transmitting member during continued movement of said operating element, a gripping mechanism, 20 a lever device connected between said gripping

mechanism and said operating element, said lever device being mounted for movement from one side to the other of a dead-centre position, a servo spring-mounted to hold said lever device on one side of the dead-centre position, said lever device being so operatively associated with said force-transmitting member that when the latter is impeded, said lever device is forced over the dead-centre position by the continued movement of said operating member, whereby said gripping mechanism is engaged to provide an abutment against which said servo spring acts in relaxing to expend energy on said operating element during still further movement of the latter, and a subsidiary spring connected to oppose said servo spring until said lever device is forced over the dead-centre position and thereafter to assist in the engagement of said gripping mechanism. 10 15
